DESIGN FOR A RADIO PHONOGRAPH CABINET

Leland George Stone, Fort Wayne, Ind., assignor
to The Magnavox Company, Fort Wayne, Ind.,
a corporation of Delaware

Application April 30, 1947, Serial No. 138,701

Term of patent 7 years

(Cl. D56—4)

To all whom it may concern:

Be it known that I, Leland George Stone, a citizen of the United States, residing at Fort Wayne, in the county of Allen and State of Indiana, have invented a new, original, and ornamental Design for a Radio Phonograph Cabinet, of which the following is a specification, reference being had to the accompanying drawing, forming a part thereof.

In the drawing:

The single figure of the drawing is a front perspective view of a radio phonograph cabinet showing my new design.

Both sides are the same and the rear is conventional.

I claim:

The ornamental design for a radio phonograph cabinet, substantially as shown and described.

LELAND GEO. STONE.
